CLAMPING MEMBER

Anton J. Petkus, Chicago, Ill., assignor to Western
Electric Company, Incorporated, New York,
N. Y., a corporation of New York

Application October 6, 1938, Serial No. 233,543

2 Claims. (Cl. 179—122)

This invention relates to clamping members and particularly to clamping members for securing parts of devices in assembled relation.

A primary object of this invention is to provide an improved clamping member for securing parts of devices in assembled relation which is simple in construction and adapted to be applied and removed in a facile manner.

In accordance with the above object the invention in one embodiment thereof is illustrated as applied to the securing of an electrode assembly to a supporting bridge member of a telephone transmitter unit and comprises a centrally apertured circular clamping member formed with outer and inner peripheral flanges, the outer flange being endlessly corrugated or crimped and adapted to be pressed into holding relation with a cooperating circular extension semi-circular in cross-section formed on the peripheral edge of a neck portion of the bridge member, while the edge of the inner flange bears against an element of the electrode assembly.

In another embodiment of the invention the clamping cap is corrugated or crimped upon its outer flange after its association with the parts to be clamped together.

Other objects and advantages of the invention will more fully appear from the following detailed description, taken in connection with the accompanying drawing, in which

Fig. 1 is a cross sectional view of a telephone transmitter of a well known type embodying the clamping member of this invention;

Fig. 2 is an enlarged fragmentary view, partly in section, of the transmitter unit carrying the electrode assembly included in the telephone transmitter of Fig. 1, shown in reversed position;

Fig. 3 is a fragmentary plan view of Fig. 2, and

Fig. 4 is a fragmentary sectional view of another embodiment of the invention in which the outer flange of the clamping member is corrugated after being mounted in position to secure the parts.

In the drawing the invention is shown applied for purposes of illustration to a well known type of electrical device, such as a telephone transmitter. Referring particularly to Figs. 1, 2 and 3, a transmitter casing 10 has mounted therein a transmitter unit 11 which is clamped at one side against an annular shouldered surface 12 of the casing and at its opposite side is engaged by a shouldered surface 13 of a cap 14 screw threaded onto the casing. In Fig. 2 the transmitter unit 11 is shown without its supporting casing 10 and in a reversed position corresponding to its posi-

tion during assembly. The transmitter unit 11 includes a bridge member 17 having a shouldered aperture 18 in which is carried an electrode assembly 19 which is supported on an annular surface 20 of the aperture. Interposed between the surface 20 and the adjacent surface of the assembly 19 is a silk cloth washer 21 and a spider like supporting member 22 therefor.

The electrode assembly 19 includes brass and ceramic members 25 and 26, respectively, suitably cemented together as indicated at 27 and so shaped internally to provide a chamber 28 for granular carbon 29 entered through an aperture 30 in the member 25 which is then closed by a cap 31 pressed inwardly around an outwardly flared circular neck portion 32 of the member 25. Engaging an annular surface 33 of the electrode member 25 and closely surrounding the inner peripheral surface of the aperture 18 of the bridge member 17 is a phenol fibre washer 34, the outer surface of which is disposed slightly within an upper end surface 35 of a circular neck portion 36 of the bridge member 17. A further description of the telephone transmitter and unit 11 thereof to which the clamping member to be presently described is applied is not believed necessary for a full understanding thereof and its application.

In order to secure the electrode assembly 19 to the bridge member 17 there is provided a circular clamping member 40 formed of metal of a suitable thickness and having the desired characteristics. Formed in the member 40 is a central aperture 41 through which projects the neck portion 32 of the electrode member 25. The member 40 at its outer periphery is formed with, as viewed in Fig. 2, a downwardly extending flange 42 which is continuously corrugated or crimped, as indicated at 43. Also formed on the member 40 and surrounding the periphery of the aperture 41 is a downwardly extending continuous flange 44. The depths of the flanges 42 and 44 are such that when the member 40 is in clamping position as shown in the drawing, the lower edge surface of the flange 44 will be in pressing engagement with the upper surface of the washer 34 of the electrode assembly and the lower edge surface of the corrugated flange 42 will lie in a suitable distance above the adjacent upper surface of the bridge member 17. Also, it will be noted that the lower annular surface of the member 40 between the flanges 42 and 44 is in spaced relation with the upper annular surface 35 of the neck portion 36 of the electrode member 25.

Formed on the peripheral edge of the electrode neck portion 36 is a continuous circular beaded flange or extension 48 which is semi-circular in cross-section. The diameter of the electrode neck portion 36, through the extension 48, relative to the inner diameter of the corrugated flange 42 of the clamping member 40 is such that when the member 40 is pressed downwardly onto the extension 48 the flange 42 yields slightly in an outward direction. At the completion of the clamping operation the lower edge of the flange 44 of the member 40 will have firmly pressed the electrode assembly 19 against the surface 20 of the bridge member 17 and the corrugated flange 42 will be in firm gripping relation with the circular extension 48 of the bridge member. During the clamping operation a slight flexing in an outward direction of the upper annular portion of the member 40 about the outer peripheral edge thereof occurs. This flexing takes place after the lower edge of the flange 44 is firmly pressed against the electrode assembly 19 and just before the corrugated flange 42 is in complete gripping relation with the circular extension 48 of the bridge member 17. The pressing of the member 40 into clamping relation with the bridge member 17 may be effected by a suitable forming chuck comprising radially movable jaws while the transmitter unit is supported in any well known manner. To remove the clamping member 40 one end of a suitably shaped tool may be inserted between the lower edge of the corrugated flange 42 and the opposed surface of the bridge member 17, and upon pressing the opposite end of the tool downwardly the member 40 will be readily released.

It is to be understood that the granular carbon 29 is entered into the chamber 28 after the electrode assembly 19 is clamped to the bridge member 17 and thereafter the cap 31 secured in position.

Fig. 4 illustrates another embodiment of the invention comprising a clamping member 50, which is substantially similar to the previously described clamping member 40, except that it is formed initially with an uncorrugated outer peripheral flange 51 which fits around a square edged circular flange or extension 52 of the neck portion 36 of the bridge member 17. An inner continuous flange 54 of the clamping member 50 is similar to the corresponding flange of the previously described embodiment and serves in an identical manner thereto. In applying the member 50 it is first positioned around the extension 52 of the bridge member with the lower edge sur-

face of the inner flange 54 engaging the upper surface of the electrode assembly 19. While thus positioned a suitable pressure is exerted against the upper surface of the member 50 at substantially the point indicated by the arrow 55 and simultaneously therewith the flange 51 is pressed inwardly and corrugated or crimped, as indicated at 56, around the portion thereof disposed below the extension 52 by a suitable forming chuck comprising radially moving jaws provided on their inner surfaces with forming teeth. Pressure at the arrow 55 is for the purpose of preventing the upper annular portion of the member 50 between the flanges 51 and 54 from being drawn downwardly at its outer peripheral edge and contacting with the upper surface of the neck portion 36 of the bridge member 17 during the corrugating operation with a consequent releasing of the pressure of the inner flange 54 on the electrode assembly 19.

From the foregoing description, it will be apparent that a simple and practical arrangement has been devised for firmly clamping together parts of devices particularly parts of telephone transmitters. Furthermore, the arrangement permits an expeditious assembly of the parts as well as the release thereof.

While the features of this invention have been disclosed in a specific structure, it is, of course, understood that various modifications may be made without departing from the scope of the invention as defined in the appended claims.

What is claimed is:

1. In a telephone transmitter unit, a supporting member having an aperture, an electrode unit within the aperture, an annular engaging shoulder on the supporting member, and a clamping member having inner and outer flanges, the inner flange clamping the electrode unit within the supporting member aperture and the outer flange corrugated to provide a clamping action around the annular engaging shoulder.

2. The combination, with a telephone transmitter unit having a supporting member, an annular engaging shoulder thereon and a recess within which is supported an electrode unit, of an apertured sheet material clamping member through which a portion of the electrode unit extends and having inner and outer flanges, said clamping member engaging at its outer flange the annular engaging shoulder with a yielding crimping action and the inner flange engaging the electrode unit when the clamping member is pressed into position.

ANTON J. PETKUS.
